UNITED STATES PATENT OFFICE.

WILLIAM C. WEAVER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TRUNKING SYSTEM.

Application filed May 22, 1924. Serial No. 714,999.

This invention relates to telephone trunking systems, and more particularly, to systems wherein a plurality of link or trunk lines are required.

5 The object of this invention is to provide an improved trunking system having as its outstanding characteristic great flexibility of trunk selection.

In accordance with this invention a number of trunks are divided into groups, each group accessible to a trunk finder switch adapted to hunt thereover and to seize the first idle trunk in the group. A steering or pilot switch is likewise provided which has 10 access to each of the trunk finder switches and is adapted to pilot or steer a calling line to one of the trunk finder switches in the group whereby an idle trunk is selected, the steering switch being controlled in turn by 15 the trunk finder switch, so that in case all the trunks in the group are busy, the trunk finder switch causes the steering switch to advance and pilot the calling line by way of the next trunk finder switch in the group to 20 the group of trunks accessible thereto, and the cycle of operations is repeated.

It is believed that a more thorough understanding of the invention may be obtained from the description which follows:

25 Fig. 1 shows a calling line, a cord circuit for answering the calling line and the jack end of a trunk outgoing to a distant mechanical central office.

Fig. 2 shows the trunk finder and steering switches and the operator's control equipment.

When the receiver is removed at the substation 1, Fig. 1, the line relay 7 operates and lights the line lamp 9. The call is answered by inserting the plug 32 in the jack 2, operating the relays 8 and 11 and extinguishing the line lamp 9. The listening key 33 is operated and the office code and line number of the desired line are obtained. 40 The office key 17 peculiar to the desired office is depressed, closing an obvious circuit to operate the relay 18. Relay 18 operated locks by way of 19, 31, 235, and 258 to ground. It also closes a circuit to operate relay 206 as follows: battery, winding of relay 206, 30, 20 to ground. The steering switch has no normal position and it remains in the position in which it is last used. Brush 251 shown on Fig. 2 is resting on the 45 terminals associated with the lower one of

the two trunk finders disclosed. Therefore, when relay 206 operates it, locks by way of 235 and 258 to ground, and closes a circuit to operate the stepping magnet 205 as follows: battery, winding of the stepping magnet 205, 215, 251, 216, 217, 218, 219, 252, 226, 213, 229 to ground. Stepping magnet 205 opens at 215 its own operating circuit and releases, advancing the brushes 210 to 214, inclusive, one step in an anti-clockwise direction, so that the brushes are now positioned upon the first terminal of each of the arcs 200 to 204, inclusive. The terminals of the various arcs 200 to 204 are associated with a particular group of trunks and we 50 will assume that each trunk in this group is busy, in which case, ground will be connected to each terminal in the arc 203 and a circuit will be closed as follows to operate stepping magnet 205: battery, winding of the stepping magnet 205, 215, 251, 216, 217, 218, 219, 252, 226, 213 and 227 to ground. The brushes 210 to 214, inclusive, will be advanced to the terminals associated with the next trunk in the group and as all of the 55 trunks are busy, the cycle of operations will be repeated and the brushes will advance until the twenty-first terminal in each arc is reached. This will be the only time when one of these switches will be normal as the 60 brushes remain on the terminals to which they were advanced at the time of the last call. In this position a circuit will be closed to operate the stepping magnet 205 as follows: battery, winding of the stepping magnet 205, 215, 251, 216, 217, 218, 219, 252, 226, 213 and 227 to ground. The stepping magnet 205 operated 65 closes a circuit to operate the stepping magnet 244 of the steering switch as follows: battery, winding of the stepping magnet 244, 253, 238, 239, 245, 236, 210, 237 to ground. The stepping magnet 244 operated opens its own operating circuit and releases, advancing the brushes 250 to 253, inclusive, one step in an anti-clockwise direction. As 70 the brush 250 advances, the circuit previously traced for retaining the stepping magnet 205 operated is opened, releasing this stepping magnet and advancing the brushes 210 to 214, inclusive, another step, in which 75 position brushes 210, 211, 212 and 214 are opened, only brush 213 remaining in contact with the terminal 229. A circuit is now closed to operate the stepping magnet 225 of the trunk finder which has access to the next 80

trunk. The stepping magnet 225 operated closes a circuit to operate the stepping magnet 205 as follows: battery, winding of the stepping magnet 205, 215, 251, 216, 217, 218, 219, 252, 226, 213 and 227 to ground. The stepping magnet 205 operated opens its own operating circuit and releases, advancing the brushes 210 to 214, inclusive, another step, in which 85 position brushes 210, 211, 212 and 214 are opened, only brush 213 remaining in contact with the terminal 229. A circuit is now closed to operate the stepping magnet 225 of the trunk finder which has access to the next 90 trunk. The stepping magnet 225 operated closes a circuit to operate the stepping magnet 205 as follows: battery, winding of the stepping magnet 205, 215, 251, 216, 217, 218, 219, 252, 226, 213 and 227 to ground. The stepping magnet 205 operated opens its own operating circuit and releases, advancing the brushes 210 to 214, inclusive, another step, in which 95 position brushes 210, 211, 212 and 214 are opened, only brush 213 remaining in contact with the terminal 229. A circuit is now closed to operate the stepping magnet 225 of the trunk finder which has access to the next 100 trunk. The stepping magnet 225 operated closes a circuit to operate the stepping magnet 205 as follows: battery, winding of the stepping magnet 205, 215, 251, 216, 217, 218, 219, 252, 226, 213 and 227 to ground. The stepping magnet 205 operated opens its own operating circuit and releases, advancing the brushes 210 to 214, inclusive, another step, in which 105 position brushes 210, 211, 212 and 214 are opened, only brush 213 remaining in contact with the terminal 229. A circuit is now closed to operate the stepping magnet 225 of the trunk finder which has access to the next 110

group of trunks leading to the same office as follows: battery, winding of the stepping magnet 225, 246, 247, 251, 216, 217, 218, 219, 252, 248, 233, 249 to ground. Stepping magnet 225, in operating, opens at 246 its own operating circuit and releases, advancing the brushes 230 to 234, inclusive, one step in an anti-clockwise direction, and positioning them upon the first terminal of the arcs 220 10 to 224, respectively.

Let us assume that all the trunks in this group except the one represented by the leads 26, 27, 28 and 29 are busy, in which case, all the terminals of the arc 233 except 15 terminal 254 will be grounded, and the circuit to operate stepping magnet 225 (previously traced) will be again closed and the brushes will be advanced and positioned upon the second terminal of each of the arcs 20 220 to 224, inclusive. This cycle of operations will continue until brush 233 is positioned upon the terminal 254. Since this trunk is idle, the lead 28 will be free from ground, hence, the stepping magnet 225 will 25 not reoperate. A circuit is now closed to operate relay 207 as follows: battery, winding of the stepping magnet 225, 246, 251, 216, 217, winding of relay 207, 255 to ground. The stepping magnet 225 will not operate 30 over the circuit traced due to the high resistance of the winding of relay 207 in series with it. It should be observed that so long as the trunk finder switches were hunting for an idle trunk the relay 207 was 35 prevented from operating in series with the stepping magnet 205 or 225 due to the solid ground connected to either the brush 213 or the brush 233. Relay 207 operated connects solid ground to the lead 219, thence by way 40 of brushes 252 and 233 to the terminal 254 of the trunk circuit, causing this trunk to test busy to all other trunk finder switches.

The trunk circuit having been found the 45 operator's control equipment 256 is set in a manner (not shown) to indicate the number of the selected trunk to the operator. As the trunk number indicating device forms no part of this invention, it is not described herein. A complete explanation of the operation of a suitable trunk number indicating device is given in the United States Patent 50 to Clark 1,456,537, issued May 29, 1923.

The operator's control equipment may also 55 when necessary include a register sender such for example as the one shown in Figs. 9, 10, and 11 of the patent of Allen, No. 1,513,362, October 28, 1924.

When the operator's control equipment 60 has performed its necessary functions, the plug 4 will be inserted in jack 5 operating relay 14 over an obvious circuit, closing a circuit to operate relays 6 and 208 as follows: battery, right winding of relay 6, 34, 29, brush 234, 257, through the control equipment 256 (in a manner not shown), winding

of relay 208, 237 to ground. Relay 208 operating opens at 258 the locking circuit for relay 206 which releases, in turn, releasing relay 207. The release of relay 207 opens the circuit through relay 208 which releases 70 and the operator's control equipment is restored to normal.

When relay 6 operated over the circuit previously traced, it locked through its windings in series by way of 35 and 16 to 75 ground. Relay 6 operated extends the outgoing trunk circuit to equipment at the distant mechanical office DMO.

If the operator's control equipment Fig. 2 includes the register sender, the switches 23 80 and 24 at the distant mechanical office DMO have already been set over leads 26 and 27 in a manner not shown, but which is fully described in the patent of Allen, supra. If the operator's control equipment does not 85 include a register sender the switches 23 and 24 may be set by means of a dial (not shown) connected to the cord circuit Fig. 1.

In any event, the called station 25 is signalled and answers and the talking connection is established. When the receiver is replaced upon the switchhook at the calling station 1, relay 11 releases and the supervisory lamp 10 is lighted as a disconnect signal. When the receiver is replaced on the switchhook at the called station 25, relay 12 releases and the lamp 13 lights as a disconnect signal. When the plugs 32 and 4 are removed from the jacks 2 and 5, respectively, 95 relays 8, 14 and 6 release, and the circuit is 100 restored to normal.

While for purposes of illustration the invention has been disclosed in connection with a telephone system between a manual and a mechanical central office, it is not so limited, but may be used as a trunk finder in any signaling system wherein the use of a large number of trunks or link circuits necessitates the division of such trunks or links into a number of equivalent groups. 110

What is claimed is:

1. In a trunking system, a plurality of trunks arranged in groups, a plurality of trunk selectors, there being as many trunk selectors as there are trunk groups, each selector having access to any idle trunk in its particular trunk group, operating circuits for said selectors, a steering switch for successively establishing the operating circuits of said selectors therethrough to render the selectors operable, and means controlled by each trunk selector for advancing the steering switch so as to associate it with the next selector. 115

2. In a telephone system, a line, a plurality of trunk lines arranged in two or more groups, a hunting device associated with the first group, said device adapted to move over the lines in its group and to seize the first idle line therein, a second hunting 120 130

device similarly associated with respect to the second group, a steering switch adapted to establish the operating circuits of said hunting devices in succession therethrough, 5 and means included in the first hunting device effective when all lines accessible thereto are busy for advancing the steering switch to render the second hunting device operable.

10 3. In a telephone system, a line, a plurality of other lines arranged in groups, a hunting device associated with the first group, said device adapted to move over the lines in its group and to seize the first idle 15 line therein, a second hunting device similarly associated with respect to the second group, a third hunting device similarly associated with respect to the third group etc., a steering switch adapted to establish the 20 operating circuits of said hunting devices in succession therethrough, and means included in each hunting device effective when

all lines accessible thereto are busy for advancing the steering switch to render the 25 next hunting device operable.

4. In a telephone system, a pilot switch, a plurality of hunting devices to the operating circuits of which said pilot switch has access in succession, a plurality of groups of lines, there being one group of lines per 30 hunting device, means for causing the hunting device whose operating circuit is connected to said pilot switch to hunt for and seize an idle line in its group, and means controlled by the hunting device so connected for operating the pilot switch whereby the latter advances and connects with the operating circuit of the next succeeding hunting device and the cycle of operations is 35 repeated.

In witness whereof, I hereunto subscribe my name this 19th day of May A. D. 1924.

WILLIAM C. WEAVER.
